ARTHUR L. PROUT, OF GLENDALE, CALIFORNIA, ASSIGNOR TO ADRIAN R. REYNOLDS,
OF LOS ANGELES, CALIFORNIA.

COLLAPSED-CASING ROLLER.

Application filed November 28, 1924. Serial No. 752,703.

It is the object of this invention to provide means for expanding collapsed pipe, casing, and the like, to its original cylindrical contour, the device being particularly adapted for use in connection with the casing of an oil well.

More particularly it is the object of the invention to provide expanding means adapted to be rotated in a casing, and having a tapering nose carrying rotatable pein contact means arranged in universal bearings, so that said contact means may rotate in whatever direction pressure is exerted by the tool against the collapsed casing walls for reshaping and expanding the same.

It is a further object of the invention to provide a tool having a nose for initially expanding the collapsed walls, and also having a cylindrical body in rear of said nose with anti-frictional contact means mounted thereon so as to reshape the expanded casing walls to their original cylindrical contour.

It is a still further object of the invention to provide a shoulder at the rear of the tool, tapering in the opposite direction to that of the nose of the device, and provided with contact means adapted to expand the casing as the tool is withdrawn therethrough, in the event of partial collapse of the walls in rear of the tool after insertion thereof in the casing.

It is a still further object of the invention to provide extremely simple but positive means for mounting the contact means on the tool, the arrangement of the parts permitting of the ready removal and replacement of the contact members mounted on the cylindrical body of the tool.

It is a still further object of the invention to provide roller contact members on the cylindrical body of the tool, said rollers bearing against the body of the tool and being held in place by pins having said rollers loosely journaled thereon.

It is a still further object of the invention to provide means for supplying a lubricant adjacent the point of engagement of the contact means with the wall of a collapsed casing; and to also provide for continuously supplying the lubricant throughout operation of the tool.

The invention will be readily understood from the following description of the accompanying drawings, in which:—

Fig. 1 is a front elevation of the tool partly in axial section.

Figs. 2 and 3 are transverse sections on the lines 2—2 and 3—3 of Fig. 1.

Fig. 4 is a detail vertical section showing the method of mounting the contact balls in the tool.

The tool comprises a shank 1 having an undercut shoulder 2 whereby it may be engaged by a fishing tool in the event of accidental displacement: the shank being provided with a coupling pin 3 at its upper end so that the tool may be suspended from a usual string of rotatable drill pipe which is adapted to be lowered into the collapsed well casing.

At the lower end of shank 1 the tool flares to an enlarged diameter so as to form an annular tapering surface 4, said surface being operative during withdrawal of the tool from the casing, to expand any restriction formed in the casing wall in rear of the tool after its insertion in the well.

Below the tapering surface 4 the body of the tool is cylindrical, and forms annular shoulders 5 and 6 at the respective ends of an elongated medial portion which is of reduced diameter so as to form an annular recess 7.

A nose for the tool depends from the cylindrical body portion, said nose comprising a conical member 8 having its base abutting against the lower end of the cylindrical body, and detachably fixed thereto by a pin 9 projecting axially from said body and threaded into a cooperating recess 10 in the base of the nose piece.

Rotatable contact members are mounted on the nose 8 and are adapted to rotate in any plane depending upon the direction in which pressure is exerted by the tapering nose against the collapsed casing walls. As an instance of this arrangement the contact members are shown as balls 11 projecting slightly beyond the peripheral surface of the nose, and a ball 11^a projecting beyond the slightly truncated end of the nose. The balls are received in bearing recesses 12 formed in the surface of the nose, so that

said balls may rotate in any direction, the edges of said recesses being peined over the surfaces of the balls to a slight extent, as shown at 13 in Fig. 4, in order to hold said 5 balls in place.

Contact members are also mounted on the cylindrical body of the tool for rotation upon axes parallel to the axis of the tool, said contact members comprising elongated rollers 14 journaled in the annular recess 7, with their outer sides projecting slightly beyond the body of the tool. The rollers 14 preferably taper to a slightly reduced diameter toward their forward ends, and bear against 10 the base of annular recess 7 which is correspondingly tapered so as to form a bearing surface throughout its length.

The rollers are held against radial displacement by pins 15 extending through 20 axial bores 16 of said rollers, the ends of said pins being received in bearing apertures 17 which extend through shoulders 5 and 6. The bearing apertures extend all the way through said shoulders, and the upper ends 25 of the apertures in shoulder 5 at the rear end of the tool, are of reduced diameter so as to form end abutments 18 for preventing axial displacement of pins 15 in one direction. The pins are held against axial displacement 30 in the opposite direction by abutment of nose 8 against the shoulder 6, a construction which permits of ready removal and replacement of the pins and rollers by disconnecting the nose 8 from the body portion of the tool, 35 so that pins 15 may be withdrawn through the apertures 17 in the shoulder 6. When the pins are to be thus withdrawn, they may be readily dislodged by a suitable tool inserted in the open ends of the apertures 17 40 which extend through shoulder 5.

Washers 19 are preferably mounted on pins 15 between the ends of the rollers and the adjacent surfaces of shoulders 5 and 6, and the rollers are loosely mounted on pins 45 15 so as to bear directly against the base of recess 7. By this construction the rollers are free to rotate and pins 15 are relieved of any strain.

Contact members rotatable in any plane 50 are also mounted on the tapering surface 4 of the tool, said members comprising balls 11^b projecting slightly beyond surface 4 and journaled in corresponding bearing recesses 12^b, as explained in connection with balls 55 11 and 11^a.

By the construction as thus described it will be seen that when the tool is rotated and gradually forced downwardly between the collapsed walls of a casing, the balls 11 60 and 11^a will engage the restricted portion of the casing, and due to the taper of nose 8, will gradually expand said walls; and the rollers 14 will then engage the expanded walls, and by continued rotation of the tool as it is 65 forced downwardly, the rollers will reshape

the walls of the casing to their original cylindrical contour. When the tool is subsequently withdrawn, the balls 11^b of tapering surface 4 will engage any restriction which may form in the casing above the tool, so as to expand said casing and thus permit the 70 free removal of the tool.

The ends of rollers 14 are preferably curved as shown at 20 so as to provide a gradual transition from the contact surface 75 of either nose 8 or taper 4 to the contact surface of rollers 14, in order to prevent end abutment of said rollers against any restriction formed by the collapsed casing walls. The tool will thus be continuous in 80 its operation and will be free of any tendency to stick or bind as it is withdrawn or inserted.

In order to lubricate the surface of the collapsed casing which is engaged by the 85 contact means of the expanding member, an axial bore 21 extends through shank 1 so as to communicate with the bore of the drill pipe upon which the tool is mounted, and a suitable lubricant is forced downwardly 90 through the drill pipe and into bore 21. The bore 21 is adapted for discharge of the lubricant adjacent the contact means of the tool, and as an instance of this arrangement bore 21 terminates above the annular recess 95 7, and branch bores 22 extend therefrom and open through the tool at the upper end of recess 7 opposite the respective rollers 14. The lubricant may thus be discharged 100 from the tool throughout operation thereof.

The tool may be made in various sizes for use in connection with casing of different diameters, and the tools of each size are adapted for small variation in the diameter of the circle described by the contact surfaces of rollers 14, in order to adapt the tool to differences in internal diameter of casings of the same size, as is caused by the use of casing material of different thicknesses.

For this purpose bearing apertures 17^a 110 are formed through shoulders 5 and 6 of the tool, in radially spaced relation beyond apertures 17 and in circumferentially spaced relation between said apertures. The rollers 14 may thus be replaced by rollers 14^a 115 of slightly greater diameter as shown in dotted lines in Fig. 3, the pins 15 on which said larger rollers are mounted being received in the apertures 17^a, so that said rollers will bear against the base of annular recess 7 and will form a contact surface of slightly increased diameter.

I claim:—

1. A device of the character described comprising a body portion and a tapering 125 nose at one end thereof, the opposite end of said body forming a surface tapering in the opposite direction, and rotatable contact means on said tapering surface.

2. A device of the character described 130

- comprising a member having a bearing recess extending longitudinally thereof at its periphery, a roller in said recess bearing against the base of the same, and a pin 5 having said roller loosely journaled thereon with the ends of the pin projecting beyond the respective ends of the roller and extending into said member.
3. A device of the character described 10 comprising a member having a medial portion of its length of reduced diameter to form an annular peripheral recess, rollers in said recess projecting beyond the periphery of said member and bearing against the base of said recess, and pins having said rollers loosely journaled thereon and extending into said member at the ends of said recess.
4. A device of the character described 15 comprising a body portion and a detachable nose, rollers journaled on said body, supporting pins for said rollers, and bearing apertures in said body adapted to receive said pins, said apertures opening through the end of said body adjacent said nose whereby said pins are removably held in said apertures by the abutment of said nose against the end of said body.
5. A device of the character described 20 comprising an expanding member, rollers having pins projecting axially from both ends thereof and mounted in said member, and means for radially adjusting the mounting of said pins at both ends of the roller.
6. A device of the character described 25 comprising a member having the medial portion of its length of reduced diameter to form an annular peripheral recess having annular shoulders at the ends thereof, said shoulders having circumferentially spaced apertures formed therein and arranged in sets radially spaced one beyond another, pins adapted to be received in the apertures of either set, and rollers in said medial recess on said pins.
7. A device of the character described 30 comprising an expanding member having means for connecting the same to a hollow support, and rotatable contact members on the periphery of said member, said expanding member having a bore opening through the end thereof into said hollow support and communicating with the rotatable contact members.
8. A device of the character described 35 comprising an expanding member, and a rotatable contact member at the periphery thereof, said expanding member having a bore opening therethrough at the rotatable contact member.
9. A device of the character described 40 comprising a body portion and a detachable nose, contact means journaled on said body, and means for retaining the contact means on the body extending into the end of the body adjacent said nose whereby said retaining means are removably held by the abutment of the nose against the end of the body.
10. A device of the character described 45 comprising a member having a peripheral recess, bearing apertures in said member at the ends of said recess and arranged in sets spaced radially one beyond another, contact means in said recess, and retaining means 50 for said contact means adapted to be received in the bearing apertures of either set.
11. A device of the character described 55 comprising an expanding member having means for connecting the same to a hollow support, and rotatable contact means on the periphery of said member, said expanding member having a bore communicating through one end with said hollow support 55 and open at its opposite end through said expanding member.
12. A device of the character described 60 comprising a member having a peripheral recess, contact means in said recess, and a pin having said contact means journaled thereon with the ends of the pin projecting beyond the respective ends of the contact means and extending into said member.
- In testimony whereof I have affixed my 65 signature to this specification.

ARTHUR L. PROUT.
